Primary Examiner — Michelle E. Wilson*Assistant Examiner* — Caitlin A Laverty(74) *Attorney, Agent, or Firm* — KOLITCH ROMANO
DASCENZO GATES LLC(57) **CLAIM**

The ornamental design for a hydration reservoir, as shown and described.

DESCRIPTION

FIG. 1 is a top front isometric view of a hydration reservoir showing the new design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed lines shown in the drawings illustrate portions of the hydration reservoir that form no part of the claimed design.

1 Claim, 6 Drawing Sheets# US D1,083,356 S
